DESIGN FOR A WRENCH

Archibald C. Brintnall, Denver, Colo.

Application August 31, 1945, Serial No. 121,763

Term of patent 14 years

(Cl. D54—16)

To all whom it may concern:

Be it known that I, Archibald C. Brintnall, a citizen of the United States, residing in the city and county of Denver and State of Colorado, have invented a new, original, and ornamental Design for a Wrench, of which the following is a specification, reference being had to the accompanying drawing, forming part thereof.

In the drawing:

I claim:

The ornamental design for a wrench, as shown.
ARCHIBALD C. BRINTNALL.
